UNITED STATES PATENT OFFICE.

WILLIAM A. BONNELL, OF BROOKLYN, NEW YORK, ASSIGNOR TO FOUNTAIN ELECTRICAL FLOOR BOX CORPORATION, A CORPORATION OF NEW YORK.

UNIVERSAL FLOOR-BOX.

1,136,929.

Specification of Letters Patent. Patented Apr. 27, 1915.

Application filed May 20, 1913. Serial No. 768,728.

To all whom it may concern:

Be it known that I, WILLIAM A. BONNELL, a citizen of the United States, residing in the city of Brooklyn, in the county of Kings and State of New York, have invented certain new and useful Improvements in Universal Floor-Boxes, of which the following is a full, clear, and exact description, such as will enable others skilled in the art to which it pertains to make, construct, and use the same, reference being had to the accompanying drawings, and to letters of reference marked thereon, forming a part of this specification.

15. My invention relates to an improved universal floor box to receive electric conduits and wires at a point at which they are brought into compartments of buildings on the floor level. This floor box is designed 20 to receive any kind of a commercial receptacle on the market, such as for instance, electric light fixtures, switches, fuse plugs, sockets, or the like.

The floor box may be embedded in a floor 25 of a building, and it may be adapted for use in other locations, as for instance, in the ceiling or wall of a room.

The object of my invention is to provide a universal floor box of this character, having 30 two adjustable box body sections and resilient means interposed or clamped between said sections to make the box perfectly water-tight and which may be adjusted readily and accurately to any construction or character of floor or wall, and which is readily accessible to permit renewal and repair of the socket or fuse plug or any other receptacle which may be contained in the floor box.

40. Other objects will appear from the description hereinafter given.

A preferred form of the invention is illustrated in the accompanying drawings, which form a part of this specification, the 45 numerals of reference indicating the several and similar parts in the respective figures, and in which—

Figure 1 represents a sectional view of a floor box constructed in accordance with my 50 invention. Fig. 2 represents a plan view of the same, with the cover removed. Fig. 3 represents a plan view of the lower section. Fig. 4 represents a similar view of the 55 clamping ring, to which a strap supporting a switch or fuse plug may be fastened. Figs.

5 and 6 represent plan and side views of the strap designed to support a switch or fuse plug. Fig. 7 represents a side elevation of the same strap showing the different ways in which a switch or fuse plug is carried by said strap. Fig. 8 represents a fragmentary section of a modified form of the upper and lower box sections provided with means for firmly securing the sections in position when properly adjusted; and Fig. 9 represents in cross-section, a view of the gasket not compressed.

The floor box proper consists of an upper and lower section numbered respectively 1 and 2. These sections are preferably of cylindrical shape and formed of cast iron, although they may be of any shape and configuration, as for instance, the lower box section may be made polygonal.

3 represents a yielding annular gasket 75 made of rubber, leather, felt, or any analogous material, which gasket is secured to the upper box section by the clamping ring 4. The clamping ring 4 is provided with a series of screw-threaded holes 5, for the reception of screws 6, which pass through suitable apertures 7 located in the interiorly arranged projections 8 formed integral with the box body 1. In this manner, the annular gasket is secured to and carried by the 80 upper box section. In order to properly adjust and secure the upper and lower box sections together and at the same time make the box thoroughly water-tight, it is only necessary to insert the upper section into the 85 lower section, or vice versa, and then tighten up on the screws 6 until the upwardly projecting portion of the annular gasket 3 is forced or brought into intimate contact with the interior wall of the lower section 2 and 90 the exterior wall of the upper section 1.

Increased pressure brought to bear upon the gasket 3 by means of the clamping ring 4 will unite and adjust said sections in a position and efficient manner. The arrangement 100 and interposition of the gasket 3 between the body section insures a thoroughly water-tight joint, and in order to more firmly secure the sections in position when properly adjusted, I may provide the interior of the 105 upper portion of the box section 2 and the exterior of the lower portion of the box section 1 with a series of depressions 9, arranged in any convenient or suitable manner, entirely or partly around said sections, 110

into which, by means of increased pressure from the clamping ring, the gasket will be forced into engagement with said depressions 9, as clearly indicated in Fig. 8 of the drawings.

The gasket 3 is preferably made annular in form with a wide, flat base designed to be supported on the clamping ring 4 and a cylindrical outer peripheral surface designed 10 to engage with the upper inner cylindrical surface of the lower box section 2. The inner peripheral surface of the gasket is preferably concaved, as clearly indicated in Fig. 9 of the drawings, to somewhat conform to the lower outer portion of the upper box section 1, and for the reason that when the gasket is secured to the upper box section 1 as previously described, and said section, together with its attached gasket and ring, 20 are inserted in the lower box section, further pressure brought to bear upon the gasket 3, by means of the clamping ring 4 and screws 6, will force the gasket material into intimate contact with the inner and outer 25 walls of the lower and upper box sections, uniting and adjusting said sections in most positive and efficient manner.

As a further means of adjusting and securing the box sections 1 and 2 together, I 30 may employ the means illustrated in Figs. 1 and 2 of the drawings, which consists in providing the upper section 1 on the inside with the two inwardly projecting lugs 10 and the lower section 2 with corresponding 35 lugs 11, the lower lugs 11 being screw-threaded to receive screws 12, one of which passes through an aperture 13 formed in the lug 10 and the head of the other screw bearing against the under side of the lug 40 10, the head being accessible by means of the aperture 14 in said lug 10. By turning the screws 12, the two sections 1 and 2 may be adjusted toward or from each other.

15 represents a cover which may be secured to the upper box section 1 in any well-known manner, provided with a nozzle 26 having screw-threaded engagement with said cover. An insulating bushing 16 for the passage of the conductors (not shown) is secured in the upper end of the nozzle. I 45 interpose rubber gaskets 17 and 18 between the cover 15 and upper section 1, and between the recess formed in the cover and the nozzle 26 to make a water-tight joint.

50 19 represents a strap or bridge carrying a switch or fuse plug 20, provided with notches or slots 21 in the longitudinal sides thereof. This strap 19 is provided with an offset portion 22 to which the switch or fuse 55 plug 20 may be secured by means of screws or the like passing through apertures 23. The strap is secured to the lugs 24 formed on the clamping ring 4 by screws (not shown) which engage with screw-threaded 60 apertures 25 in the lugs 24. The slots 21

formed in the longitudinal sides of the strap or bridge 19 furnish ready means whereby the strap or bridge with its attached switch or fuse plug 20 may be easily and quickly secured to or removed from the clamping ring 4. The slot 21, together with the offset portion 22 also enables me to secure the strap to the clamping ring 4 in two different positions, as for instance, when a large switch or fuse plug is used in connection with a flat cover, I prefer to arrange the strap in the box as indicated in the dotted lines in Fig. 1 of the drawings, and where a box with a projecting nozzle, such as is shown in Fig. 1 of the drawings is used, I secure the strap to the switch or fuse plug in the manner indicated in dotted lines in Fig. 7 of the drawings.

While I have shown my preferred form, it will be understood that many modifications may be made to accomplish the same results without departing from the spirit and scope of my invention.

I claim:

1. A floor box having two adjustable box body sections, an adjustable clamping ring carried by one of said sections and resilient means carried by said clamping ring, said resilient means interposed between the ring and said sections for connecting said box sections together in their adjusted positions.

2. A floor box having two adjustable box body sections, one section provided with securing means, an adjustable clamping ring carried by said securing means, and a gasket carried by said ring, said gasket being interposed between the ring and said sections for connecting said box sections together in their adjusted positions.

3. A floor box having two adjustable box body sections, one section being provided with an outwardly projecting flange at its top edge, and with an inwardly projecting flange at its bottom edge, a clamping ring suspended from said inwardly projecting flange and a gasket carried by said ring and adapted to engage with said sections for firmly securing the sections together in position when properly adjusted.

4. A floor box having two adjustable box body sections, one section being provided with an outwardly projecting flange at its top edge and with an inwardly projecting flange at its bottom edge, a clamping ring carried by said inwardly projecting flange, a strap carrying a switch or fuse plug secured to said clamping ring, a gasket carried by said ring and adapted to engage with said sections for firmly securing the sections together and means for firmly securing the sections and gasket in position when properly adjusted.

5. A floor box having two adjustable box body sections, a clamping ring carried by

one of said sections, and a gasket provided with a flat under side and with an outer cylindrical and an inner concave surface, said flat surface adapted to engage with the 5 clamping ring, and the outer cylindrical and inner concaved surfaces adapted to engage with said box body sections, thereby connecting said box sections together and means for

firmly securing the sections and gasket in position when properly adjusted. ¹⁰

This specification signed and witnessed this eighth day of April, 1913.

WILLIAM A. BONNELL.
